ARTHUR M. HARTLEY
INVENTOR.

BY *G. Lorenz Hartley*

UNITED STATES PATENT OFFICE

2,631,734

APPAREL HOLDER

Arthur M. Hartley, Decatur, Ill.

Application August 16, 1950, Serial No. 179,666

4 Claims. (Cl. 211—32)

1

This invention relates to apparel holders, being an improvement on a prior application, Serial No. 76,721, now abandoned, filed February 16, 1949, and without limitation thereto has more particularly to do with one of this type adapted for being removably mounted on a door so as to enable articles of wearing apparel to be conveniently held thereon.

An object of the invention is to simplify and make practical and convenient such a device, having easily and effectively manipulable means for placement of articles of clothing either for temporary convenience or for storage.

A further object is the provision of assembly and adjustable features not heretofore provided in apparel holders of this class, and which present in my invention certain qualities of economy, convenience, strength, and novelty.

Other objects and advantages to be attained will hereinafter more fully appear in the following description and the accompanying drawings which set forth a practical though non-limiting exemplification of my invention.

In the drawings:

Figure 1 is a side elevation.

Figure 2 is a projected plan view taken on a plane parallel with the inclined portion of Figure 1.

Figure 3 is a top plan view of the showing in Figure 1, and,

Figure 4 is a front elevation of Figure 1.

Having reference to the drawings in detail, and referring first to the Figure 1, the numeral 10 designates the suspension plate adapted for engagement over the top of a door, and which, by means of its bearing portion 11 swingably supports the vertically positioned twin-wire suspension member 12, its bottom end being bent in substantially U-shape so that its elongated twin wires are substantially parallel arranged, while their upper ends are turned inwardly toward each other to engage said bearing portion 11 as at 12'.

The incliningly positioned twin-wire suspension member 13 is also swingably supported by the suspension plate 10, and though it has the same U-shape bottom end form and the same elongated twin wires, substantially parallel arranged, still the upper ends of these wires are turned outwardly from each other, the opposite of those of the member 12, in order to swingably engage the pair of bearing portions 14 which are spaced apart a certain distance so that when said outwardly turned upper ends of the member 13 are in assembled position (see Figs. 2 and 4), the in-

2

wardly facing corners of the upper ends of said member 13 inwardly impinge the twin-wires of the member 12 in yieldable spring-like engagement as at 14' to position and firmly hold the member 12 against the plate 10. This engagement may be broken, of course, by a relatively strong pull outwardly on the lower end of the member 12, away from the plate 10, as for example, in disassembling the device for packing.

10 Now, referring particularly to Fig. 1, the horizontal connecting rod member 15 serves to position the member 13 with respect to the member 12, connecting the two, and thus enabling garments to be suspended from the member 15. The inner end of the member 15 has formed thereon the loop 16 covered by a suitable insulating sleeve 17 to rest against the door and insulate the same from abrasive action of said loop 16. The member 15 is rebent at its outer end as at 15' to form 15 the hook part 18, the mouth 19 of which is opened just enough to exert a substantially firm frictional contact when the lower end of the member 13 is removed from or brought into engagement with said hook 18 as the case may be.

20 The relatively short tube member 20 of yieldable and friction inducing material, such as rubber, plastic, or the like, slidably engages the twin-wires of the member 13, and is provided with a pair of aligned holes 20' extending laterally therethrough and adjacent the upper face 30 thereof and adapted for mounting the frame element 21.

Said frame element 21 is of horseshoe-like form, its open end having right-angularly and downwardly extending parts 22 and 23, which in turn have formed from their lower ends the inwardly extending horizontally arranged portions 24 and 25 respectively, adapted for slidable and frictional engagement in said aligned holes 20' of the tube member 20. The portion 24 is rebent at its inner end to form the rest bar 24' which slidably engages the top surface of the member 13 in order to maintain a suitable position of the frame element 21 as shown especially in the Fig. 1.

It will appear obvious from reference to Fig. 2 that the frame 21 may be made narrower or wider as desired, by simply pressing inwardly or else drawing outwardly the two portions 24 and 50 25 to accommodate various sizes of headgear placed thereon, as represented by the broken lines Z. The frictional holding action in the tube member 20 enables it to remain in fixed though movable position at any point to which it may be 55 moved along the length of the member 13, and,

likewise, the frame element 20 will remain in any suitable width to which it may be adjusted as described, one width being indicated by the dotted lines X.

It is here noted that upon the release of the lower end of the member 13 from engagement with the hook 18 of the member 15, which may be accomplished by raising the outer end of said member 15, the members 13 and 15 may be collapsed against the member 12, thereby effecting a relatively flat and compact group, greatly facilitating its packaging for shipping or storage.

The peculiar construction and arrangement of parts of my present invention, not only enables practical production at reasonable cost, but also effects an article well adapted for the purpose intended, in that it is built and assembled as to provide a maximum of rigidity, strength, and usefulness in actual practise.

Although the structure as herein described and illustrated in the accompanying drawings, is a practical exemplification of the invention, it is not presented as a limitation, as modification and change therein may be made and is even contemplated within the scope of the appended claims.

What is claimed is:

1. An apparel holder of the type herein described, comprising in combination a suspension plate, a pair of suspension members swingably supported by the suspension plate, means on the suspension plate for releasably holding one of said suspension members against said suspension plate, a connecting rod member engaging the pair of suspension members, a yieldable tube member mounted on one of the suspension members, and a supporting frame member mounted on said tube member.

2. An apparel holder of the type herein described, comprising in combination a formed suspension plate, a pair of twin-wire suspension members swingably supported by the suspension plate, means on the suspension plate for releasably holding one of said suspension members against said suspension plate, a connecting rod member having a loop formed at one end and an open hook formed at the other end thereof, and releasably connecting said pair of suspension members, a relatively short yieldable tube member slidably mounted on one of said suspension members, an adjustable supporting frame member slidably mounted on the tube member.

3. An apparel holder of the type herein described, comprising in combination a suspension plate of substantially inverted channel formation, a vertically positioned twin-wire suspension member swingably supported by the suspension plate, an inclinedly positioned twin-wire member also swingably supported by said suspension plate, means on the suspension plate for enabling the upper portion of said inclinedly positioned twin-wire members to impinge the twin wires of said vertically positioned twin-wire member intermediate the ends thereof to releasably hold said vertically positioned suspension member against the suspension plate, a horizontally positioned connecting rod member having a loop formed at its inner end swingably engaging the lower end of said vertically positioned twin-wire member and an open hook formed at its outer end engaging the lower end of said inclinedly positioned twin-wire suspension member, thereby to

enable the suspension of garments from the connecting rod member, a relatively short yieldable tube member for the frictional and slidable engagement of said inclinedly positioned member

5 6 a substantially horseshoe shaped adjustable frame member slidably mounted on said tube member, means on said tube member for enabling the laterally slidable adjustment of said frame member to increase or diminish its width to 10 accommodate various sizes of headgear placed thereon.

4. An apparel holder of the type herein described, comprising in combination a formed suspension plate of substantially inverted channel

15 formation, bearing means in said plate to swingably support a pair of suspension members, a vertically positioned twin-wire suspension member having elongated parallelly arranged wires joined in substantially U-shape at their lower

20 ends and turned at right-angles inwardly at their upper ends to engage said bearing means on the suspension plate, an inclinedly positioned twin-wire suspension member having elongated parallelly arranged wires joined in substantially

25 U-shape at their lower ends and turned at right-angles outwardly at their upper ends to engage said bearing means on the suspension plate, said bearing means so arranged and spaced as to cause the upper ends of the twin wires of

30 the inclinedly positioned suspension member to releasably inwardly impinge the twin wires of said vertically positioned suspension member intermediate the ends thereof to releasably hold said vertically positioned suspension member

35 against the suspension plate, a horizontally positioned connecting rod member having a loop formed at its inner end, an insulating covering on said loop, said loop adapted for swingably engaging the lower end of said vertically positioned twin-wire member and an open hook formed at the outer end of the connecting rod

40 member to engage the lower end of said inclinedly positioned twin-wire suspension member, a relatively short yieldable tube member for the frictional and slidable engagement of the twin wires of the inclinedly positioned member, means on the tube member for slidably mounting a frame member, a substantially horseshoe-shaped laterally adjustable frame member slidably mounted

45 50 on said tube member, means on said frame member for maintaining it in position parallel with the inclinedly positioned suspension member on which it is mounted.

ARTHUR M. HARTLEY.
